UNITED STATES PATENT OFFICE

154,111

DESIGN FOR A COMBINED DISPLAY RACK
AND COLOR SELECTOR

Robert L. Falkenberg, Mission, Kans.

Application April 26, 1948, Serial No. 145,971

Term of patent 7 years

(Cl. D80—9)

To all whom it may concern:

Be it known that I, Robert L. Falkenberg, a citizen of the United States, residing at 6113 Lockton Lane, Mission, in the county of Johnson and State of Kansas, have invented a new, original, and ornamental Design for a Combined Display Rack and Color Selector, of which the following is a specification, reference being had to the accompanying drawing, forming a part thereof, wherein:

Fig. 1 is a front perspective view of the combined display rack and color selector, showing my new design.

Fig. 2 is an end elevational view of the same.

Fig. 3 is a top plan view of the same.

Fig. 4 is a front elevational view of the same.

Fig. 5 is a rear elevational view of the same.

I claim:

The ornamental design for a combined display rack and color selector, as shown.

ROBERT L. FALKENBERG.
